UNITED STATES PATENT OFFICE.

LOUIS C. GERKEN, OF NEW YORK, N. Y.

DESIGN FOR A SPRING FOR BOTTLE-WASHERS.

SPECIFICATION forming part of Design No. 29,540, dated October 25, 1898.

Application filed September 27, 1898. Serial No. 692,029. Term of patent 14 years.

To all whom it may concern:

Be it known that I, LOUIS C. GERKEN, a citizen of the United States, residing at New York, in the county of New York and State of New York, have invented and produced a new and original Design for Springs for Bottle-Washers, of which the following is a specification, reference being had to the accompanying drawings, in which—

10 Figure 1 is an edge view thereof. Fig. 2 is a plan or face view thereof, and Fig. 3 a sectional view on a line 3 3 of Fig. 1.

15 The leading feature of my design consists of the shape or general contour of the spring, which is straight for a portion of its length, but curved in cross-section, then curved in its length, but flat in cross-section, and then, finally, to its lower end straight in the direction of its length, but curved in cross-section.

20 A represents the body of the spring, which is curved, as shown, in the direction of its length, but flat in cross-section, while its lower end B is curved in cross-section, as shown in Fig. 3, but straight in its length, as shown in Fig. 1.

25 The upper end C of the spring from the point *a* to the extreme end thereof is straight in the direction of its length, but curved in cross-section, as shown in Fig. 3.

30 What I claim is—

The design for a spring for bottle-washers, substantially as herein shown and described.

LOUIS C. GERKEN.

Witnesses:

GEORGE COOK,
M. VAN NORTWICK.
